(57) **CLAIM**

The ornamental design for a spray container, as shown and described.

DESCRIPTION

FIG. 1 is a top perspective view showing my new design for the spray container together with broken lines representing associated structures;

FIG. 2 is a bottom perspective view thereof;

FIG. 3 is a top perspective view shown without the associated structures;

FIG. 4 is a bottom perspective view thereof;

FIG. 5 is a front elevational view thereof;

FIG. 6 is a back elevational view thereof;

FIG. 7 is a left side elevational view thereof;

FIG. 8 is a right side elevational view thereof;

FIG. 9 is top plan view thereof;

FIG. 10 is bottom plan view thereof; and,

FIG. 11 is cross sectional view taken along line 11-11 of FIG. 9.

The broken line showing of an example fire extinguisher or repellent sprayer in FIGS. 1 and 2, and of the example gauge in FIG. 2, is included to illustrate an operating environment of the spray container and forms no part of the claimed design.
